UNITED STATES PATENT OFFICE.

JOHN T. DRIGGERS, OF TAMPA, FLORIDA.

STOP GAUGE.

Application filed February 24, 1925. Serial No. 11,326.

This invention relates to improvements in stop gauges particularly well adapted for use by carpenters, cabinet makers and other tradesmen to facilitate the cutting of particular lengths of material such as moulding, rods, and the like.

The primary object of this invention is the provision of an improved stop gauge, of a relatively simple character, which embodies 10 a novel arrangement of supporting stop blocks adaptable to be used so that particular lengths of material may be cut without disturbing prior adjustments.

A further object of this invention and an 15 important one is the provision of an improved stop gauge, adapted to be used with a conventional type of miter box, and embodying an improved arrangement of stop blocks which may be utilized in connection 20 with the support of the work and in connection with the proper stopping of the work to permit the accurate length to be cut.

A further object of this invention is the provision of an improved type of stop block 25 as an article of manufacture.

Other objects and advantages of this invention will be apparent during the course of the following detailed description.

In the accompanying drawings, forming 30 a part of this specification, and wherein similar reference characters designate corresponding parts throughout the several views,

Figure 1 is a plan view of the improved gauge, showing the same in an associated 35 relation with the miter box.

Figure 2 is an elevation of the improved stop gauge, showing the same in associated 40 relation with a miter box and a piece of work, with the same relation of details as is illustrated in Figure 1.

Figure 3 is a fragmentary view, partly in section, taken substantially on the line 3—3 of Figure 1.

Figure 4 is a perspective view of the novel 45 type of stop block embodied in the improved gauge.

Figure 5 is a cross sectional view taken substantially on the line 5—5 of Figure 3.

Figures 6 and 7 are cross sectional views 50 taken substantially on their respective lines in Figure 2 of the drawings, these views preferably illustrating the working size of the gauge details.

Figure 8 is a perspective view of a type of 55 support adapted to be used in connection with the gauge.

In the drawings, wherein for the purpose of illustration is shown only a preferred embodiment of the invention, the letter A may generally designate the improved stop gauge, 60 which is adapted to be used in a novel co-operating relation with a conventional type of miter box B.

The miter box B, as is well known includes a bottom 10, upon the upper surface 11 of 65 which work is adapted to be placed. The miter box furthermore includes side walls 12, and they together with the bottom 10 are provided with an arrangement of slots 15, to permit cutting of pieces of work at the desired angle. The miter box of course opens 70 at the end thereof.

Referring to the improved stop gauge A, the same preferably includes a supporting board or plate 20, elongated to the proper 75 length. In the preferred construction of the gauge for conventional use, the same will vary in length from 6' to 10' 6", although these dimensions may be departed from if desired. The support 20 is of the appropriate length, and at the ends thereof is provided with the supports or standards 21, which are of analogous formation, and which are illustrated in Figures 1 and 8 of the drawings. These supports 21 include the base 22, 80

and arranged at a corner thereof is the up-standing rod supporting portion 23, having a transverse opening 25 therethrough for supporting an end of the stop block support rod 26. The rod support portion 23 is placed 85 so that the outer surface thereof lies flush with an edge 26^a of the base 22, and the supports 21 are so placed upon the platform 20 that the said outer surface of the rod support portion 23 and edge 26^a of base 22 are 90 flush with the end edges of the platform 20, so that the miter box B may abut against the flush surfaces and properly position the same accurately, at all times with respect to the stop gauge A. The supports 21 are only 95 placed in the relation defined at the ends of the platform 20, but it is to be noted that the base 22 lies over the upper surface of this platform, and does not project beyond the edges thereof, and it is provided with openings 29 therein for receiving securing elements by means of which the standards or supports 21 may be secured to the platform 20. The rod 26 is of one piece formation, 100

and is of the desired length. It extends 110 longitudinally above the platform 20, in spaced relation thereover, and is supported 105

in the openings 25 of the supports 21 so that the ends of said rod lie inwardly of or flush with the outer surfaces of the supports 21, and said rod ends do not project beyond the supports 21. The rod 26 is thus supported adjacent the longitudinal edge 30 of the platform 20, and the stop blocks C are adjustably supported on the rod 26, extending laterally in right angled relation therefrom, over the platform 20, and in the relation to be subsequently described. The rod 26 it will be noted is clamped in a rigid relation with respect to the standards 21 by means of set screws 35, of the thumb operating type, which are adjustable in screw threaded openings 36 in the top of the standards 21, and as is illustrated in the drawings.

The stop blocks C are of novel construction, including the attaching portion 38, and the work supporting and stop extension 39 integral therewith. The attaching portion 38 is provided with an opening 40 therein by means of which the stop blocks C may be assembled on the support rod 26. The rear edge 41 of the attaching portion 38 is concentric with this opening 40, and the stop block extension 39 is preferably provided with a plane bottom surface 43, contiguous with the arcuate edge 41. The attaching portion 38 adjacent the juncture of the same with the extension 39 provides a work abutting edge 45, which is at right angles to the top work supporting edge 46 of the extension 39. The outer end edge 47 of the extension 39 is rounded off, to facilitate use of the stop block.

Referring to the assemblage of the stop blocks C on the rod 26, as above mentioned each attaching portion 38 is received on the rod 26, and a thumb operated clamp screw member 50 is adjustable in a screw threaded opening 51 at each of the stop block attaching portions 38; the same being radially disposed in the opening 40, and adapted to clamp in setting relation against the rod 26, whereby to firmly position the stop blocks C in the desired relation with respect to the platform 20. The stop blocks C as illustrated in the drawings, at the outer lower corner of the extension 39 may abut on the platform 20, when the stop block C is in lowered work supporting relation, and in this event the work supporting surface 46 of the extension 39 will be horizontal, and the work abutting edge 45 will be vertical. In this position of the stop blocks, illustrated in Figure 7, the stop block does not perform its function of providing a stop for the work, but provides a support upon which the work is placed so that the said work may abut against a stop block further along the line which is elevated into stopping position, as is illustrated in Figure 6 of the drawings.

When the stop block is to be used as such,

the same may be elevated by first releasing the said set screw 50, until the extension 39 is elevated above the platform 20, at the desired angle, as is illustrated in Figure 6 of the drawings, and so that a piece of work 70 D which is supported by the miter box and upon the stop blocks between the elevated stop block and the miter box may be slid into abutment against the side edge of the extension 39, and as is illustrated in Figures 75 1, 2 and 6 of the drawings.

In connection with each stop block C, a clamping collar 60 is provided therefor, which is of ring shaped formation, and adapted to be slipped over the rod 26, at 80 the opposite side of its respective stop block C with respect to the miter box B. Secured in this ring 60 is a set screw 61 of the thumb operating type, adjustable in a screw threaded opening 62, as is illustrated in 85 Figure 5 of the drawings, so that the clamping collar 60 may be secured in a rigid adjusted relation on the supporting rod 26. This clamping collar 60 in connection with its stop block serves two important functions. 90 The first of these functions is that the said clamping collar reinforces the clamped position of each stop block C against movement longitudinally of rod 26. Also, it can readily be understood that the clamping collar 60 of a particular stop block C being set on the rod 26, permits the operator to release the stop elevated position of the block C and lower the same into abutment with the platform 20, so that it may be temporarily used 100 for work supporting purposes, and a stop block further along the line elevated to perform the stop function.

As the rod 26 will be of considerable length, to prevent sag of the same it is preferred to provide novel supporting members 65 therefor, between the ends of the rod 26, which include a ring shaped portion 66 having an opening 67 therethrough for receiving the rod 26, and also including an integral depending foot 69 which at its lower edge rests on the top surface of the platform 20. This ring 66 is provided with a set screw 70 of the thumb type, operating in a screw threaded opening 72, and adapted for clamping against the rod 26 to secure the support device 65 in the desired position to support the rod 26 intermediate its ends against liability of sag.

Referring to the use of the improved device, the miter box B abuts against the end edge of the platform 20, and also abuts against the flush surfaces of the supports 21. In this position the miter box is accurately placed with respect to the device A, and it is to be noted that the top surface 11 of the miter box 10 is horizontally positioned flush with the horizontal top edges 46 of the stop blocks C, when they are lowered into their work supporting relation as 130

- is illustrated in Figures 1, 2 and 7 of the drawings. When the device A has been so assembled with respect to the miter box B, the particular stop block which regulates the length of the piece of work D is elevated as is illustrated in Figure 6 of the drawings, so that its extension 39 extends in intersecting relation across the plane provided by the flush surface 11 and edges 46. 10 When the stop block to serve, as such, has been adjusted into its proper position along the rod 26, and elevated above the platform 20, it is clamped in this position, and its clamping collar 60 is set squarely against the same, to prevent any further liability of slipping of the stop block out of adjustment. The piece of work D is then laid upon the bottom 10 of the miter box, and on the extensions 39 of the lowered blocks 15 C and is moved along until its end edge abuts against the elevated stop block C, as is illustrated in Figure 1 of the drawings. The piece of work is thus properly positioned so that the saw may cut into the desired slot 15 of the miter box properly severing the piece of work D. In connection with the operation as above described, it is to be noted that the stop block C serves an important function in providing an abutment for the longitudinal edge of the work piece D. Thus the work D is slid along the lowered stop blocks until the same abuts the shoulders 45, and it is properly stabilized and held in exact parallel relation 20 with respect to the rod 26, and in exact co-operating relation against the miter box B; the inside surface of one wall 12 of the miter box being flush with the work abutting shoulders 45 of the lowered blocks C, and as is illustrated in Figure 1 of the drawings. 25

From the foregoing description of this invention it is apparent that a novel type of stop gauge has been provided, which is particularly well adapted to be used in connection with the sawing of lengths of material such as moulding, iron rods, timber, and the like. The same may be used to cut lengths of material without disturbing prior 30 adjustments, and enables a very accurate cutting of the lengths of material incident to the fact that the stop blocks which are lowered between the miter box and the elevated stop blocks serve as abutments to properly align the piece of work with respect to the miter box. 35

Various changes in the shape, size, and arrangement of parts may be made to the form of invention herein shown and described, without departing from the spirit of this invention or the scope of the claims. 40

I claim:

1. In a stop gauge the combination of a base, supporting uprights on the base, a rod carried by said uprights, and a plurality 45 of blocks supported in laterally extending relation by said rod, each having a work supporting surface, each of said blocks including means to clamp the same to the rod, said blocks when in lowest position to engage the base having the work supporting surfaces thereof arranged in substantially the same plane. 50

2. In a stop gauge of the class described a supporting rod, means mounting the rod, a plurality of stop blocks independently adjustable on the rod, each of said stop blocks including a work supporting edge upwardly thereof, and means for limiting the amplitude of adjustment of the stop blocks so that said work supporting edges may be disposed in the same plane for the purpose of supporting a piece of work, and across which plane any of said stop blocks may be positioned for work limiting purposes. 55

3. In a stop gauge the combination of a horizontally supported rod, a plurality of stop blocks adjustably clamped to said rod, each of said blocks including an upper work supporting edge and a work abutting edge, arranged transversely to the work supporting edge, and means to limit the lowered adjustment of said blocks so as to dispose the work supporting edges in the same plane and the work abutting edges in another plane whereby one of said blocks when elevated from its lowered position may intersect said planes to limit the movement of a piece of work supported by said blocks. 60

4. In a stop gauge the combination of a supporting platform, uprights carried by the platform, a supporting rod fixed in said uprights in horizontal relation over said platform, stop blocks pivotally carried by said rod, clamps for fixing the stop blocks in a desired laterally extending relation from the rod, said stop blocks when lowered with their free ends engaging the platform providing upper edges horizontally disposed in the same plane and work abutting side edges at the ends of said upper edges disposed in a vertical plane, any of said stop blocks when elevated from their lowered position being adapted to pass across the planes provided by said upper and side edges. 65

5. In a stop gauge the combination of a rod, standards supporting the rod in fixed relation, a plurality of stop blocks adjustably clamped to said rod, a support, each of said stop blocks when lowered to engage the support providing a horizontal upper edge all of which are disposed in the same plane and a work abutting edge vertically disposed at right angles to the work supporting horizontal edge all of which vertical edges are disposed in a vertical plane, said edges being so arranged on the work blocks that when one of said work blocks is elevated from its lowered position it may intersect said planes and provide an obstruc- 70 75 80 85 90 95 100 105 110 115 120 125 130

tion against which work may abut to limit the movement thereof.

6. In a stop gauge of the class described a supporting base, uprights carried at the ends of said base, a rod supported by said uprights horizontally over said base, laterally extending stop blocks pivoted on said rod, clamp means for each of the stop blocks for securing them to the rod, a collar 10 carried by the rod relatively movable with respect to each of said stop blocks, means for clamping said collar to the rod, each of said stop blocks when lowered engaging said base to limit the lowest movement thereof, 15 and when thus lowered providing an upper horizontally disposed work supporting edge and an end vertically disposed work engaging edge, said horizontal edges and vertical edges of the stop blocks which are lowered 20 being disposed in the same plane.

7. As an article of manufacture a stop block for stop gauges having an opening therethrough at one end thereof and providing a lateral extension having a plane 25 top edge and a side edge disposed substantially at right angles to said plane top edge at an end of said plane top edge adjacent said opening.

8. As an article of manufacture a stop block for stop gauges comprising a substantially ring shaped attaching portion having an opening therethrough, a set screw carried by said attaching portion adjustable into the opening thereof, and a lateral work supporting and abutting extension having a plane top edge and a right angled abutting edge at an end of said top edge adjacent said attaching portion of the stop block.

9. In a stop gauge combination of a supporting rod, a base upon which the rod is mounted in spaced relation thereabove, a plurality of stop blocks apertured for pivotal mounting at an end of each on said supporting rod, means to clamp each of said stop blocks in a rigid relation on said supporting rod, each of said blocks having a lower surface sloping from adjacent said rod to the outer end thereof and adapted to be diagonally positioned with respect to the plane of the top surface of the base, each of said stop blocks having a top work supporting surface horizontally positioned when the stop blocks rest upon said base as indicated and a side stop edge transversely of the top work supporting edge.

JOHN T. DRIGGERS.
